(57) CLAIM

The ornamental design for a jar with a lid, as shown and described.

DESCRIPTION

FIG. 1 is a top view of the present design;

FIG. 2 is a bottom view thereof; and,

FIG. 3 is a side view, the other three sides being mirror images thereof.

The broken lines showing the pattern on the top and bottom portions of FIG. 3 represent surface ornamentation which does form part of the claimed design.
